METHOD OF MAKING A SHEET METAL BARREL

Daniel J. Reed, Milwaukee, Wis., assignor to A. O. Smith Corporation, Milwaukee, Wis., a corporation of New York

Application October 14, 1933, Serial No. 693,531

* 2 Claims. (Cl. 113—120)

This invention relates to a method of making barrels formed of sheet metal and having a substantially cylindrical side wall and two end heads welded thereto.

5 The object of the invention is to provide a simple and economical method for making such a barrel, and which obtains an improved quality of structure and weld, whereby the barrel is enabled to withstand rough usage.

10 Other objects will appear hereinafter.

The accompanying drawings illustrate a barrel made in accordance with the invention and:

Figure 1 is a side elevational view with parts broken away and in section showing the details 15 of construction;

Fig. 2 is a detail section of one end of the barrel showing the assembly of the parts;

Fig. 3 is a similar section showing the spinning operation; and

20 Fig. 4 is a similar section showing the final welding operation.

The barrel comprises, generally, a substantially cylindrical body portion 1, a bottom head 2, a top head 3, and preferably has a central bilge band 4.

25 The body 1 of the barrel is preferably formed of sheet metal rolled into a cylinder and welded on a longitudinal seam 5. After welding, the body may be slightly bilged, if desired, by employing an expanding mandrel.

The bilge band 4 is of heavier metal to give strength and protection to the central portion of the barrel and is formed of arcuate cross-section with its ends 6 conforming to the shape and size 30 of the body 1 and suitably secured thereto.

35 A suitable bung fitting 7 is welded to the body 1 at its inner end and to the bilge band 4 at its outer end to provide access to the inside of the barrel. The bilge band 4 serves to protect and 40 reinforce the bung 7.

The bottom end head 2 is pressed from a single sheet of metal and is preferably dished downwardly at its central portion and provided with a downwardly extending flange or skirt 8 at its 45 outer edge adapted to fit into the end of the body 1.

In making the barrel in accordance with the invention, the end head 2 is inserted in the lower end of the body 1 the desired distance, preferably until the edge of the flange 8 corresponds with the end edge of the body 1, as shown in Fig. 2. Then the barrel is positioned in a spinning machine and a shoulder 9 is spun in the wall of body 1 immediately adjacent the inner 55 corner of the head 2, as illustrated in Fig. 3.

This spinning operation results in the formation of a circumferential groove 10 in the outer wall of the body 1 near the end and of a corresponding rib or bead 11 on the inside of the wall. The bead 11 provides the shoulder 9 against 5 which the end head seats tightly throughout the circumference. The spinning operation is preferably carried out cold, that is, without heating the metal, although care should be taken where a high carbon or other high strength steel is 10 employed not to embrittle the metal at the shoulder 9 by too much cold working.

After the spinning operation, the barrel is placed in a suitable welding machine and the head 2 is welded to the body 1 at the shoulder 9, 15 as shown in Fig. 4. The tight fit between the head 2 and shoulder 9 effected by the spinning operation greatly facilitates the welding operation and the production of a fluid-tight joint. The weld is preferably an electric resistance stitch 20 weld such as is made by employing two roller electrodes arranged to pass the welding current through the joint and simultaneously therewith to apply the welding pressure, the weld being made progressively circumferentially of the joint. 25 The roller electrodes are shaped to conform to the contour of the head and shoulder, respectively, so as to obtain a good fluid-tight weld.

The top end head 3 is constructed similarly to the bottom head 2 except that its flange 12 extends upwardly. The head 3 is positioned in the top end of the body 1 and a shoulder 13, spun in the body 1 adjacent the head similarly to the shoulder 9 at the bottom head. The top head is then welded to the body 1 at the shoulder 13 35 in the same manner as the bottom head is welded at the shoulder 9.

The top head 3 may have a suitable tap connection 14 therein. Suitable chimes 15 are provided at the ends of the barrel to protect the 40 end edges of the body 1 and flanges 8 and 12.

The construction provided by the invention has numerous advantages in use. When a loaded barrel is dropped on one corner, the shock is transmitted to the body portion through the 45 beads 11 which cushion the shock and tend to prevent undesirable deformations of the barrel. Furthermore, the crevice between the lower end head and the side wall at the bead 11 tends to close as the bead is flattened by the shock, thus 50 preventing separation of the parts which would tend to crack the pitch lining 16 at the corner of the barrel. Excessive deformation of the head is also prevented by having the weld in substantially the same plane as the head, and the bead 55

strengthens the side wall and head against deformations.

I claim:

1. In the manufacture of sheet metal barrels
- 5 having a substantially cylindrical body portion and an end head, the steps comprising, inserting the head to its final position in the body portion, forming a shoulder in the body portion against the corner of the head, and welding the head to
- 10 the shoulder to provide a fluid-tight joint.
2. In the manufacture of sheet metal barrels

having a substantially cylindrical body portion and an end head, the steps comprising, inserting the head to its final position in the body portion of the barrel, spinning a groove in the outer wall of the body portion adjacent the head to provide a circumferential shoulder on the inside of the body against which the head seats, and electric resistance welding the head to the body portions at said shoulder.

5

DANIEL J. REED. 10
